UNITED STATES PATENT OFFICE.

GEORGE W. KNOX, OF OKLAHOMA, OKLAHOMA.

ANIMAL POKE.

Application filed August 24, 1921. Serial No. 494,869.

To all whom it may concern:

Be it known that I, GEORGE W. KNOX, a citizen of the United States, residing at Oklahoma, in the county of Oklahoma and 5 State of Oklahoma, have invented certain new and useful Improvements in Animal Pokes, of which the following is a specification.

This invention relates to animal pokes 10 and has special reference to the type of device disclosed in Letters Patent No. 1,322,120, granted to me November 18, 1919. The object of the present improvements is to facilitate the manufacture of the device 15 and reduce the cost thereof and also to provide a construction which will permit the pricking prongs to be more rapidly applied or removed. The invention is illustrated in the accompanying drawings and will be 20 hereinafter fully set forth.

In the drawings—

Figure 1 is a perspective view of the device showing it applied;

Fig. 2 is a side elevation of the device;

25 Fig. 3 is a front elevation partly in section;

Fig. 4 is a detail perspective view of the pricking prongs.

In carrying out my present invention, I 30 employ upper and lower yoke members which are adapted to be placed around the neck of the animal and secured together. Each yoke member consists of a pair of strap irons 1 which are offset intermediate 35 their ends, as shown at 2, whereby the offset portions may be brought close together and thereby produce a U-shaped member adapted to fit around the neck of the animal and diverging arms having forwardly 40 projecting wire-engaging lugs or teeth 3 at their ends. In assembling the strap irons, after the offset portions are brought together, a flat bar 4 has one end inserted between said offset portions and the said 45 bar and offset portions are then welded or otherwise intimately secured together, a bolt hole 5 being formed through the three members. The upper and lower yoke members are duplicates and the description just given 50 of one member applies in all respects to the other member. The ends of the yoke members are overlapped, as shown at 6, and are provided with registering openings through which securing bolts 7 are inserted 55 to secure the members together, and it will be readily noted that the yoke members can

be easily adjusted over and under the neck of the animal and then secured against separation, and that the flat sides of the strap irons are presented to the neck of the animal so that a smooth surface will be provided and chafing of the animal's neck will be thereby avoided. Moreover, the strap irons are all similar in design and the wire-engaging members are integral with the neck-engaging portions thereof so that the yokes may be very expeditiously and economically produced. A bolt 8 is inserted through the bolt opening 5 in each yoke member and also through the openings 9 in the forked end 10 of the pricking device which consists of diverging prongs 11 extending from a body or shank 12 at that end thereof opposite the fork 10. In assembling the parts of the poke, the fork 10 is slipped over the portions 2 of the yoke members after said offset portions have been united with the inner end of the bar 4 and the bolt 8 is then inserted through the registering openings and a retaining nut 13 turned home on the end of said bolt against the adjacent side of the fork. The pricking device may thus be very readily removed or applied and if it be desired to have the pricking prongs employed at only one end of the poke, the prong which is to be discarded may be easily removed without disassembling the entire device.

Inasmuch as the wire-engaging members are permanently united with the yoke members, separation of the parts cannot occur and the cost of manufacture of the device is very materially reduced while a stronger structure results.

In using the device, the yoke members are united about the neck of the animal, as shown in Fig. 1, with the pricking prongs extending rearwardly and the lugs or teeth 3 of the wire-engaging members projecting forwardly. Should the animal attempt to break through a fence or other barrier, the wire-engaging arms will at once bear against the fence wire strands and will cause the yoke to rock rearwardly so that the prongs 11 will prick the animal, whereupon the efforts to break through the fence will cease.

Having thus described the invention, what is claimed as new is:

An animal poke comprising upper and lower yoke members, each consisting of a pair of flat-sided straps sharply offset be-

tween their ends and permanently united at the offset portions, the opposite terminals of the yoke members being fastened together whereby to secure the members about the neck of an animal, and the outer extremities of the straps being sharply divergent, a bar secured between the offset portions of a pair of straps and projecting therefrom midway the outer diverging ter-

minals of the straps and in the plane of the same whereby said terminals and the bar will constitute a wide wire-engaging member, a fork spanning and secured to the offset portions of the straps, and prongs projecting rearwardly from said fork.

15

In testimony whereof I affix my signature.

GEORGE W. KNOX. [L.s.]
